FIG. 9

DISPENSING OF PARTICULATE MATERIAL

This invention concerns a machine for automatically dispensing small constant-weight portions of hand rolling or pipe tobacco for subsequent packing. In particular, the narrow stream feeder for preparing the tobacco in a form from which the initial portion can be dispensed with accuracy.

In known apparatus initial portions are dispensed by methods depending on volume, pressure and weight.

In one method a constant volume is dispensed by cutting a stream at regular intervals or filling a constant volume and then cutting or parting the stream. The portion is then weighed and make-up material added to correct the weight. In a refinement of this method a constant volume device is filled to a fixed pressure and the stream then cut.

In another method the portions are dispensed by feeding a small cross-section stream of material onto a weighing conveyor or pan and parting or cutting the stream when the desired under-weight has been achieved.

In all methods the initial portion is aimed at a smaller weight than that finally required and a correction is carried out by adding smaller pieces or 'fines' previously separated from the tobacco bulk. This follows from the matted nature of the material which makes it easier to add rather than deduct small corrections and also accounts for the need to cut or part the stream to produce the portions.

The efficiency of the dispenser is measured by the closeness of the initial portion to the final weight required and hence the smallness of the correction to be made.

The efficiency of the dispenser, whichever method is used is dependent on the uniformity of the narrow cross-section stream fed to the dispenser.

The efficiency of the narrow stream feeder, in fact the success of the whole machine, is measured by the uniformity of the stream it produces and especially by the extent to which it does not degrade or disintegrate the tobacco in the process of producing the uniform narrow stream.

A particular problem arises with tobacco due to the non-granular or non-fluid nature of the material coupled with the small amount to be separated, typically 0.5 to 2.0 ounces.

The tobacco used for hand rolling consists of fine shreds cut from tobacco leaf typically at 100 cuts per inch. These shreds are of variable length but generally several inches long and form individual cohesive masses or 'cobs' of entwined and matted shreds which do not easily separate, mixed with a minority of successive gradations of smaller particles or 'fines' which will separate. The moisture content is typically 25 per cent and the un-compressed bulk density typically 8 lbs/ft³ for small depths rising to 16 lbs/ft³ for depths of 2 ft. The 'cobs' are of variable size but typically around 0.1 ft³ weighing 1lb.

It is the object of the invention to enable the tobacco to be separated into very much smaller portions of accurate weights for example, portions of accurate 0.5, 1 or 2 oz. weights with a volume of approximately 4, 5, or 16 cubic inches.

For the dispenser to achieve this it must be fed with a stream or 'fleece' of tobacco of cross-section commensurate with the volume to be dispensed. A stream

or fleece of 1 to 4 ins² cross-section and 1½ to 6 oz. weight per foot length is convenient.

Hand rolling tobacco with the matted shred form described above will, by its nature, only form a uniform stream of very much larger cross-sections.

One method of achieving the narrow stream is to divide the mass of cut tobacco into its individual shreds by means of successive carding drums and then reforming a stream or fleece to the size required. This is the 10 method used in a cigarette making machine for forming the cigarette rod.

However, in cigarette tobacco the shreds are coarser, typically 50 cuts/inch and shorter typically 0.75 inch long so the amount of breaking or shortening of the 15 strands termed "degradation" is less than with the hand rolling tobacco and acceptable.

With hand rolling tobacco the customer handles the tobacco himself and the length of the strands is a standard of quality which determines how readily the hand 20 rolled cigarette holds together. It is, therefore, desirable to maintain the length of the strands in hand rolling tobacco and the amount of degradation resulting from the above method is unacceptable.

Another method of producing a small cross-section 25 stream or fleece of tobacco is to reform a much larger stream by drawing it out to the smaller cross-section.

This method most nearly matches the manual 30 method used at present in which an operating position is fed with a large cross-section stream of tobacco in a trough from which the operator draws out the small handful of tobacco required with one hand whilst holding back the main mass with the other hand.

There is inevitably some degradation with this 35 method but only that necessary to form the small cross-section compared with that necessary to substantially separate each shred by the first method.

A further object of the present invention is to provide a machine to achieve this second method in which a 40 readily formed large cross-section slow moving stream of finely cut tobacco is drawn out and accelerated into a small cross-section faster moving stream of the same density.

According to the invention we provide a tobacco 45 feeding device comprising a passage formed by a series of sections decreasing consecutively in cross-sectional area and means at each section for advancing the tobacco along said passage towards the low cross-sectional area end thereof, said means having projections which enter the tobacco during advance and 50 which effect a drawing out of the tobacco in the direction of advance at each section. In this manner the tobacco is substantially noncompressed as it passes through the passage.

The invention will be further described by way of example with reference to the accompanying diagrammatic drawings, wherein:

FIGS. 1, 2 and 3 are respectively a front elevation, side elevation and plan of a machine made in accordance with the invention,

FIG. 4 is a section on the plane IV—IV on FIG. 1, FIGS. 5 and 6 are an elevational view and plan of one of the feeding units,

FIGS. 7 and 8 are an elevational view and plan of one of an alternative form of feeding unit, and

FIG. 9 is a section on the line IX—IX of FIG. 7.

Referring to FIGS. 1, 2 and 3, the machine comprises a vertical converging passage defined by a feed tube 10,

a number of feeding unit assemblies 11, 11' and a discharge conveyor tube 13. The passage finally converges to a cross-section of for example 1.25×1.25 inch which can be more or less if desired.

In the embodiment shown, feeding unit assemblies are arranged at six levels or stations (I-VI), the units of each level being offset by 90° relative to the units of each adjacent level. More or less levels may be provided.

Each feeding unit assembly 11, 11' consists of one or more feeding units 12 each of which comprises a pair of parallel side plates 14 separated from each other by spacers 16 and a front plate 17 which faces the interior of the converging passage. (See FIGS. 5 and 6). The front plate 17 houses a pair of rockers or guide members 19, 20 mounted for oscillation about a common spindle 22 and having arcuate surfaces facing the passage. Rocker 19 has a pin 24 passing therethrough which pin is carried at one end of a pin plunger arm 25. The other end of the pin plunger arm 25 is mounted on a crank pin 27 of a gear wheel 28. Similarly, the rocker 20 has a pin 30 passing therethrough, the pin plunger arm 31 of which is mounted on a crank pin 33 of another gear wheel 34. Each pin plunger arm 25, 31 is mounted on the respective crank pin 27, 33 by way of a bearing 36, 37.

A drive shaft 40, common to the assembly, enters the unit 12 through one side plate 14 and carries a pair of drive pinions 41, 42 which respectively engage gear wheels 28, 34.

Each station or level includes an approximately square or rectangular throat. Two sides of the throat are formed by the pairs of oscillating rockers 19, 20 and the other two sides are formed by retaining plates 43 which provide continuity with the next station and with the discharge conveyor tube 13.

The pins are arranged in pairs which are spaced apart from each other and pairs of pins in the succeeding station are located between the planes of the preceding pairs.

It can be seen that the pin plunger arm 25 is considerably shorter than the arm 31 and that the driving gear wheels 28 and 34 have their centres offset from one another. Furthermore, the crank pins 27, 33 are angularly offset from each other by approximately 45° .

The feeding unit 12 operates as follows:

Rotation of the drive shaft 40 results in the rotation of gear wheels 28, 34 which carry the pin plunger arms 25, 31. As the gear wheels 28, 34 are rotated, the pin plunger arms advance the pins successively and by reason of the pivoting rockers are caused to carry out a downward swing. As each pin ends its advancing movement, it withdraws into its rocker and remains retracted while the rocker effects a return movement whereupon with the commencement of the downward movement of the rocker, the pin emerges therefrom. The action is the same for each pin except that due to the difference in length of the pin plunger arms and the relative position of the gear wheels 28, 34, the stroke and extent of penetration differ.

Therefore, the pairs of cooperating oscillating pins have the same frequency but differing amplitudes, i.e. strokes and penetrations. The longer stroke pin 24 has a shorter penetration than the short stroke pin 30 and leads it by approximately 45° phase angle. Both pins progress the tobacco down the convergent passage but with the differential pin action the long stroke pin 24

tries to progress it more than the short stroke pin with the result that the matted tobacco is drawn out in the axial direction of the passage by the long stroke pin 24 whilst being partially held back by the short stroke pin

5 30. The tobacco is therefore not compressed at any one station but is drawn out at the same time as being reduced in cross sectional area.

The tips of the pins 24, 30 thus move over paths such as those shown in FIG. 4, the tips of the pins sweeping in close proximity to the arcuate surfaces of the opposed rockers at the lower levels. As shown in FIG. 4, at each level of the converging passage feeding units are arranged in pairs on opposite sides of the channel. At level I, four pairs of feeding units 12 are provided, 15 while at levels II, III, IV, V and VI respectively three, three, two, two, and one pair of units are provided. The pins may also be progressively shorter, of smaller diameter and have less stroke.

The crank wheels may be arranged to operate the pins of any one level so that they follow each other in desired succession. The pins of level I for example enter the tobacco and as these commence retracting the pins of level II are still advancing followed in succession by the pins of levels III, IV, V and VI, each group being a sixth of a cycle out of phase with the preceding group. Hence a more or less continuous drive is imparted to the tobacco.

The pins at each level move in a plane at right angles to the pins of adjacent levels.

30 The driving speed of the pins at successive levels is increased approximately in inverse proportion to the reduction in cross-sectional area of the channel so that a constant tobacco density is maintained. At the lower levels however the pins move even faster. The throat sizes of the six levels of the example shown are respectively 37, 25, 12, 6, 3 and 1.5 square inches. The speed of rotation of the successive groups of pins are typically 1, 3, 7, 22, 85 and 200 rpm respectively.

It will be evident from FIG. 4 that the rockers 19, 20 40 at a given level constitute a converging zone X at that level, and between the converging zone there are regions Y where the walls of the channel are substantially parallel. In these regions or "cushioning" zones, the pulses set up in the tobacco by the pins are smoothed out and low frequency pulses from upper levels are prevented from passing to lower levels. To avoid any side friction within each cushioning zone Y the parallel side walls thereof are stepped out $\frac{1}{2}$ inch all round from the point of maximum convergence directly above the zone. Although the whole aim of each level of feeding is to converge the tobacco by about 2:1 without compressing it, in practice there is some slight temporary compression of the tobacco, which would result in side friction and jamming if not allowed room to re-expand.

55 The shafts 40 of the first, second, third, fourth, fifth and sixth stations are all driven from a motor 47, through a variable gearbox 48, various chains 49 and sprockets 50 and right angle gearboxes 51. The right angle gearboxes 51 may be replaced by a flexible drive if desired. Dog clutches 52 finally connect the drive to the shafts 40.

60 The motor 47 and gearbox 48 are mounted on a main frame 53 (FIG. 3) to which are pivoted two subframes, 54, 54' which carry the feeding unit assemblies 11' while the feeding unit assemblies 11 are secured to the main frame 53. Drive to the assemblies 11' includes universal joints 56, which enable the units 11' to be

swung away from the converging channel to assist cleaning etc. All the assemblies 11' of stations I, III and V are mounted on a common sub-frame 54 while assemblies 11' of stations II, IV and VI are also mounted on a common sub-frame 54'. The main frame 53 and sub-frames 54, 54' are not shown in FIGS. 1 and 2 for the aid of simplicity.

The sixth station may be followed by a short two band conveyor as shown in FIGS. 1 and 2. This conveyor is formed by a pair of plates 55 disposed parallel to each other and secured to belt guides 56, also parallel to each other, said plates and guides forming an elongate channel of substantially square section. The opposed internal surfaces of the guides support belts 58 each of which run over rollers 59 provided at the ends of the guides between the plates. At the exterior surfaces of the guides, belt drive and tensioning means (not shown) are provided.

The variable speed gearbox 49 may be adjusted by feed back signals from a subsequent weighing device to maintain a constant density of tobacco feed to a volume dispensing device. If required, a reduction or increase in density can be achieved by altering the speeds disproportionately. This method is used to control the density of the stream fed to the constant volume or constant volume and pressure type dispenser. The machine may feed via a constant volume dispenser followed by a weigher or a constant volume and pressure dispenser with a cutter followed by a weigher or to a weighing conveyor or pan with a cutter. The tobacco then feeds to a weight correction point receiving fines from the fines separator, check weigher, rejection and acceptance unit to supply the final product.

It has been found in practice that the stroke of the short stroke pin in the direction of the axis of the passage is preferably very short compared with the long stroke pin whilst the penetration of the pin into the tobacco in a direction at right angles to the axis is the same for both pins.

To achieve this short stroke but deep penetration with the simple crank mechanism shown in FIGS. 5 and 6 requires the gear wheel 34 to be moved further away from gear wheel 28 and the pin plunger arm 31 to be extended. This results in a pin unit of cumbersome dimensions, but the embodiment shown in FIGS. 7, 8 and 9 has been found to overcome this.

Referring to the embodiment shown in FIGS. 7, 8 and 9 in which like reference numerals relate to the like features in relation to the above described embodiment, a feeding unit 12 comprises a pair of side plates 14 separated from each other by spacers 16 and a front plate 17 which faces the interior of the converging passage. The front plate 17 houses a pair of rockers or guide members 19, 20 mounted for oscillation about a common spindle 22 and having arcuate surfaces facing the passage. Rocker 19 has a pin 24 passing therethrough which pin is carried at one end of a pin plunger arm 25. The other end of the pin plunger arm 25 is mounted on a crank pin 27 of a gear wheel 28. However, the pin plunger arm 31 of the pin 30 which passes through the rocker 20 is differently mounted. The pin plunger arm 31 is carried on a crank pin 60 of a planet gear 61 which in turn is carried on a crank pin 62 of gear wheel 63. The planet gear 61 engages with a ring gear 64 having exactly double the number of teeth as the planet gear 61.

A drive shaft 40, common to the assembly, enters the unit 12 through one side plate 14 and carries a drive pinion 65 which engages both gear wheels 63 and 28.

Thus, the crank pin 60 carrying the pin plunger arm 31 is driven in an elliptical instead of circular path, thereby reducing the stroke of pin 30.

It is found, using the above described device that a hopper input of 10 lb per cubic foot results in an output having a density of 12 lb per cubic foot. That is, the density remains substantially unaltered considering that the cross sectional area is reduced 24 fold (37 square inches to 1.5 square inches).

A particular advantage of the oscillating pins compared with paddles or pin drums is that the pins are self-cleaning as they are withdrawn and that there are no slots or holes in the totally enclosed convergent passage to collect tobacco and cause 'jamming'.

We claim:

1. A cut tobacco feeding device comprising a passage formed by a series of sections decreasing consecutively in cross-sectional area and means at each section for advancing the tobacco along said passage towards the low cross-sectional area end thereof, each of said means having forward and rearward oscillating projections which enter the tobacco during advance with said forward projection moving faster and having a longer stroke than said rearward projection to effect a drawing out of the tobacco in the direction of advance at each section.
2. A tobacco feeding device as claimed in claim 1, wherein said means comprise pins arranged in closely adjacent pairs, and drive means for moving each pin in such a manner that the free end thereof enters the passage during movement thereof in the advance direction and withdraws in the opposite direction of movement, the relative distance between the two free ends of the pair of pins increasing during movement in the advance direction.
3. A tobacco feeding device as claimed in claim 2, wherein the free ends of the two pins are caused to move along paths of different lengths at the same frequency, one pin moving faster than the other in the advance direction portion of the paths.
4. A tobacco feeding device as claimed in claim 3, wherein one of said pins of each pair enters the passage in advance of the other pin of said pair.
5. A tobacco feeding device as claimed in claim 4, wherein the leading pin is the faster moving pin.
6. A tobacco feeding device as claimed in claim 2, in which each pair of pins extending into the passage is opposed by another pair of pins extending into the passage from the opposite side thereof.
7. A tobacco feeding device as claimed in claim 2, further comprising a drive unit for each pair of pins, said drive unit comprising for each pin, a wheel, means for rotating said wheel, a crank pin on said wheel secured to said pin or a member attached thereto, and a guide member free to oscillate about a fixed point and through which said pin passes.
8. A tobacco feeding device as claimed in claim 2, further comprising a drive unit for each pair of pins, said drive unit for one pin comprising a wheel, means for rotating said wheel, a crank pin on said wheel secured to said pin or a member attached thereto and a guide member free to oscillate about a fixed point and through which said one pin passes, while for the other pin said drive unit further comprises a wheel, means for

rotating said wheel, a crank pin on said wheel carrying a planet gear, a gear ring engaging said planet gear and having twice as many teeth as said planet gear, a crank pin on said planet gear secured to said other pin or a member attached thereto, and a guide member free to oscillate about said fixed point and through which said other pin passes.

9. A tobacco feeding device as claimed in claim 7, in which the two wheels of each drive unit are driven from a common drive shaft.

10. A tobacco feeding device as claimed in claim 1, in which the passage comprises a plurality of converging zones in which the walls of the passage converge and in each of which said projections comprise pins which extend into said passage, said converging zones being separated from one another by a plurality of cushioning zones in which the walls of the passage do not converge and in which no pins extend into said passage.

11. A tobacco feeding device as claimed in claim 10, in which the pins of one converging zone extend into the passage at right angles to the pins of each adjacent converging zone.

12. A tobacco feeding device as claimed in claim 11, in which the cross-sectional area of each cushioning

zone is slightly greater than the minimum cross-sectional area of the immediately preceding converging zone.

13. A tobacco feeding device as claimed in claim 12, in which said frequency of movement of the free ends of the pins of each converging zone is greater than the corresponding frequency in the immediately preceding converging zone.

14. A tobacco feeding device as claimed in claim 13, in which the number of pairs of pins of each converging zone is equal to or less than the number of pairs of pins of the immediately preceding converging zone.

15. A tobacco feeding device as claimed in claim 14, in which at the large cross-sectional end of the passage, means are provided for feeding tobacco to the passage.

16. A tobacco feeding device as claimed in claim 15, in which at the low cross-sectional end of the passage, means are provided for discharging tobacco therefrom.

17. A tobacco feeding device as claimed in claim 16, in which the discharge means comprise a pair of conveyor belts on opposite sides of the passage and means for driving said belts in a direction to cause tobacco in the passage to be discharged therefrom.
